CURIO SHELF

Billy E. Alexander, Santa Monica, Calif.

Application March 23, 1956, Serial No. 40,740

Term of patent 7 years

(Cl. D33—3)

FIG. 1

I claim:

The ornamental design for a curio shelf, as shown.
